AUTOMATIC TIRE CHANGER MACHINE

John T. Curtis, Hamilton, Ohio, assignor to Magnum
Automotive Equipment, Inc., Cincinnati, Ohio

Filed June 1, 1972, Ser. No. 258,945

Term of patent 14 years

Int. Cl. D15—99

U.S. Cl. D54—13 R

FIG. 1 is a perspective view of an automatic tire changer machine showing my new design taken from the rear and one side;

FIG. 2 is a perspective view thereof taken from the front and the other side; and

FIG. 3 is a bottom view of the design.

I claim:

The ornamental design for an automatic tire changer machine, substantially as shown and described.
